UNITED STATES PATENT OFFICE.

WALTER J. BARRON, OF BROOKLYN, NEW YORK, ASSIGNOR TO THE UNION
TYPEWRITER COMPANY, OF NEW JERSEY.

TYPE-WRITING MACHINE.

SPECIFICATION forming part of Letters Patent No. 559,071, dated April 28, 1896.

Application filed June 19, 1891. Serial No. 396,840. (No model.)

To all whom it may concern:

Be it known that I, WALTER J. BARRON, a citizen of the United States, and a resident of Brooklyn, in the county of Kings and State 5 of New York, have invented certain new and useful Improvements in Type-Writing Machines, of which the following is a specification.

My invention relates to means for feeding 10 the inking-ribbon of a type-writing machine both lengthwise and crosswise, and to means for automatically reversing the direction of movement of the ribbon when the ribbon has been wound from one spool onto the other; 15 and to these ends it consists of the various features of improvement hereinafter more fully described, and particularly pointed out in the appended claims.

In the accompanying drawings, Figure 1 is a 20 top plan view of a portion of a type-writing machine embodying my invention, said machine being what is known as the "Densmore" machine. Fig. 2 is a front elevation thereof with the keyboard and other unnecessary 25 parts removed, as in Fig. 1, to avoid complication of the view. Fig. 3 is a side elevation of the machine, taken at the left-hand end and showing the improved parts in their normal positions in full lines. Fig. 4 is a similar 30 view to show the action of the parts to effect the winding and also the reversing of the ribbon. Fig. 5 is a side elevation of the machine, taken at the right-hand end, but provided with ribbon-reversing devices different 35 in construction from those shown in the preceding views. Fig. 6 is a similar view to illustrate the reversing operation. Fig. 7 is a front elevation of the machine shown at 40 Figs. 5 and 6. Fig. 8 is a perspective view of the ribbon-spool frame or support employed in the machine shown at Figs. 1, 2, 3, and 4. Fig. 9 is a perspective view of the 45 device employed for actuating the ribbon-reversing levers or switch shown at Figs. 5, 6, and 7; and Fig. 10 is a perspective view of the ribbon-spool support provided with a modified form of device for actuating the ribbon-reversing means.

Referring to Figs. 1, 2, 3, 4, and 8, 1 designates the framework of a type-writing machine; 2, the top plate or type-ring upon which

the type-levers are all mounted in any suitable way, 3 designating several of the hangars for the type-bars, which latter are not shown, in order to simplify the views.

4 is a guide-rail for the carriage 5, a portion only of which latter is shown. To the carriage at 7 is attached one end of a cord or chain 8, the other end of which is connected to a spring-drum 9, provided with a winding device 10 and let-off escapement devices 11 for decreasing the tension of the driving-drum 9. On the hub or axle of the driving-drum 9 is arranged a drum or barrel 12 to rotate with the driving-drum 9, and attached to said barrel at one end is a cord or chain 13, whose lower end is attached to the free end of a horizontal arm 14, projecting rearwardly from a collar 15 at the left-hand side of the machine, which is fast on a transverse rock-shaft 16, mounted to turn in brackets 17 at each side of the machine. Secured to said collar 15 is another vertical arm 18, whose upper free end engages loosely the left-hand ribbon-spool frame or support 19, which is perforated 20 for the reception of said arm 18. The side bars of the support 19 are each provided with a hole 21 for the passage of a rod or axle 22, which is supported fixedly in the framework by screws or centers. At the right-hand 25 side of the machine there is a similar arm 18 and a similar ribbon-spool support 19 and shaft 22. Within each frame or support 19 and upon each rod 22 is mounted to rotate a ribbon spool or bobbin 23, provided with a 30 crown ratchet-wheel 24, the spool or bobbin being held with the requisite degree of friction, to prevent it turning too easily, by means of a washer 25 between the side of the ratchet-wheel and one of the side arms of the frame 35 19, and a plate-spring 26, arranged between one head of the spool or bobbin and the other of the side arms of the frame 19, the said spring operating to press the spool against the washer and the latter against the front 40 side arm of the supporting-frame 19.

On a stud 27 at each side of the machine is pivoted a driving-pawl 28 to engage with the ratchet-wheel of each ribbon-spool and turn the same, so as to wind the ribbon lengthwise, 45 as hereinafter will more fully appear, when the ribbon-spools have been moved forward

by means of the cord 13, arm 14, rock-shaft 16, arms 18, and supporting-frames 19.

At 29 is pivoted on each ribbon-spool support 19 a lever 30, which is bent to provide a hook or eye 31 just large enough for the ribbon to pass through, but not large enough to permit the passage therethrough of a pin, bar, or other enlargement 32, with which the ribbon is provided near or at each end.

10 Pivoted at 33 on the under side of the type-ring or top plate 2 is a lever 34, curved to correspond with the curvature of the type-ring and bent laterally at each side, as at 35, then downwardly vertically, as at 36, and then 15 rearwardly horizontally, as at 37. Each vertical arm 36 of the lever is formed with an elongated slot, which embraces a pin 38, fixed to the framework, and these devices form an additional guide or support for said lever. Each 20 horizontal arm 37 of the said lever is adapted to alternately engage with its respective driving-pawl 28 and hold said pawl up out of operative relation to its ratchet-wheel 24. The lever 34 is adapted to be acted upon by the 25 lever 30, which projects forwardly beyond the support 19 when the said lever has been moved by the rod or obstruction 32 and when the ribbon-spools have arrived at or near the end of their forward movements. The ribbon 30 may be connected at its end to the ribbon-spools in the usual way—that is, by pinning or coupling the ends of the ribbon to short pieces of tape or bands secured to the ribbon-spools—or the ends of the ribbon may be attached directly to the ribbon-spools without the said tapes or bands. When the latter are used, the pins or connecting devices may operate to serve the function of the bar or obstruction 32. In lieu of either of these 35 constructions the ribbon may be bunched or so folded at or near its ends as to be incapable of passing through the eye of the lever 30.

At Fig. 3 the left-hand arm 27 of the lever 34 stands in contact with the depending end 40 of the pivoted driving-pawl 28 at the left-hand side of the machine, and by reason of this contact the upper or operating end of the said driving-pawl is held out of operative relation to the ratchet-wheel 24 and cannot turn said 45 ratchet-wheel and its spool when said ratchet-wheel is moved toward said pawl. The right-hand arm 37 of the lever 34 stands away from the lower extension of the driving-pawl 28 at the right-hand side of the machine, and the 50 gravity or construction of said pawl is such as to cause it to fall or incline rearwardly a limited distance against a stop or pin, as shown, to engage with the right-hand ratchet-wheel 24 when said ratchet-wheel arrives 55 near the end of its forward stroke, and by traveling a short distance in company with said ratchet-wheel said pawl operates to turn the same and its spool and the ribbon the distance of one notch of said ratchet-wheel.

60 At Fig. 4 the arm 37 at the left-hand side of the machine is out of contact with its driving-pawl 28, and in this condition of the parts the

left-hand pawl 28 may engage with and drive its ratchet-wheel, while the right-hand pawl 28 is prevented from engaging with or driving its ratchet-wheel. 70

Those skilled in the art will readily understand the construction and operation of the machine from what has already been said, taken in connection with the following explanation of the mode of operation of the improved mechanism. 75

At Fig. 3 the carriage is supposed to be at the extreme left-hand end of the machine and the ribbon-spools and ribbon at the end of 80 their rearward transverse stroke or movement. As the carriage is returned to the right for the commencement of a new line the cord or chain 8 is unwound from the spring-drum 9 and the cord 13 wound upon the barrel 12, 85 thereby lifting the arm 14 against the tension of the spring 40, rocking the shaft 16, and causing the arms 18 to drive or move the ribbon-spool frames or supports 19, with their accessories, toward the front of the machine. 90 As the writing progresses the spring-drum 9 gradually draws the carriage toward the left, winding up the cord or chain 8 again and allowing the cord or chain 13 to unwind and the spring 40 to gradually return the arms 14 and 95 18 and their connections to their normal positions. (Shown at Fig. 3.)

The construction and relationship of the parts are such that during the travel of the carriage from right to left the ribbon is moved 100 rearwardly transversely for substantially its whole width, and hence is being used widthwise instead of lengthwise at this time, as generally heretofore. During the travel of the carriage from left to right the ribbon is 105 moved toward the front of the machine or transversely in an opposite direction, but is not during this movement used or struck by the type-levers. When the ribbon has arrived at near the end of its forward stroke, the right-hand ratchet-wheel is engaged by the operating 110 end of the pawl 28, and as the forward movement of the ribbon and its spools is continued the said pawl is caused to vibrate or swing up forwardly and operate to turn or 115 drive the right-hand ratchet-wheel one notch or tooth, and hence move the ribbon toward the right a like distance. This movement of the ribbon lengthwise occurs at the beginning of every new line and continues until the entire length of the ribbon has been wound from the left-hand spool onto the right-hand spool. 120 As shown at Fig. 3, the ribbon has been almost entirely drawn off from the left-hand ribbon-spool and the pin or obstruction 32 is 125 soon to come into engagement with the shifting-lever 30.

At Fig. 4 I have shown the pin or obstruction 32 as having actuated the lever 30 and the latter as having acted upon the reversing-lever 34 and caused it to vibrate, so as to withdraw the left-hand arm 37 of said lever from the left-hand driving-pawl 28 and move the right-hand arm 37 of said lever into con- 130

tact with the right-hand driving-pawl, and it will be understood that, in view of the changes in position of the arms 37, the left-hand driving-pawl is now free to engage with the left-hand ratchet-wheel and wind the ribbon back onto the left-hand spool, and that the right-hand driving-pawl is restrained from co-operating with its ratchet-wheel during this time. The shifting of the lever 34, so as to provide for the reverse longitudinal movement of the inking-ribbon, is effected automatically by the projecting end of the lever 30 and in the following manner: As the obstruction 32 is unable to pass by the said lever 30, it operates to rock or vibrate the same, as indicated by the dotted lines at Fig. 3, so as to throw down its upper projecting end into a plane or position such that when the ribbon-spool frames arrive at near the end of their forward stroke the said projecting portion of said lever may contact with the lever 34 and vibrate it, so as to throw the left-hand arm 37 away from its driving-pawl and move the opposite arm 37 up against the right-hand driving-pawl, with the result hereinbefore described. As the operation of the machine is thus continued the ribbon is caused to move from right to left until near the end of its length, and when the pin or obstruction at the opposite end of the ribbon engages with and operates the lever 30 on the right-hand frame or support 19 the said lever is caused to assume a position such that it can act on the opposite or right-hand end of the lever 34 to provide for the reversal again of the ribbon.

Referring to Figs. 5, 6, 7, and 9, I have provided a substitute for the actuating-lever 30, which consists of a frame 41, provided with elongated hooks 42, adapted to rest upon the shaft 22, and having at its upper end a slot or eye 43 for the ribbon to pass through. At one side of the frame 41 is provided a projection or pin 44, which has the same function as the projecting end of the lever 30, and the slot or eye 43 is adapted to serve the same purpose that the hook or eye of the lever 30 serves—namely, to be acted upon by an obstruction in or on the ribbon and cause the projection 44 to actuate the reversing lever or switch. At Figs. 5 and 6 it will be seen that I have changed somewhat the detail construction and arrangement of the reversing-lever. In these views (5, 6, 7, and 9) I have shown a rock-shaft 45, extending across the machine in front of the ribbon, and at the left-hand end of the said rock-shaft is attached an arm 46, which at its upper end is bent to form a head 47 for the projection 44 to act against, and which below its upper end is provided with a finger 48 to act on the depending extension of the left-hand driving-pawl 28. At the right-hand end of said rock-shaft is provided a shorter arm 49 to receive the lower forked end 50 of a lever 51, pivoted at 52 to the framework, which lever is provided at its upper end with a head 47 for the

right-hand projection 44 to act against and with a finger 48 to act against the depending extension of the right-hand driving-pawl 28. The fingers 48 are arranged to act alternately on the driving-paws 28 and are adapted to perform precisely the same functions as the right and left hand arms 37 in the construction hereinbefore described.

At Fig. 5 the right-hand finger 48 is shown as resting against the right-hand driving-pawl 28 and as holding it out of operative relation to the right-hand ratchet-wheel, while the left-hand finger 48 is shown as removed from the left-hand driving-pawl 28 to allow said pawl to assume, by gravity, a position such that it may coöperate with the left-hand ratchet-wheel and turn the same and wind the ribbon to the left at each forward movement of the ribbon-spools. At said figure it will be observed that the obstruction 32 is soon to coact with the supplemental frame 41 for the purpose of effecting a reversal of the longitudinal movement of the ribbon.

At Fig. 6 the view is drawn to represent the reversal of the ribbon as having taken place. This, as before, is accomplished automatically and as follows: As the movement of the ribbon to the left continues the obstruction 32 at the right-hand side, being unable to pass through the eye or slot of the frame 41, operates to move said frame bodily and raise the pin or projection 44 to a plane or position such that it may strike the head 47 of the lever 51, on arriving at the front of the machine, and vibrate said lever about its pivot and cause the shaft 45 to be rocked and the arm 46, at the left-hand end thereof, to be thrown rearwardly and its finger 48 to contact with the lower end of the driving-pawl 28 at the left-hand side of the machine for the purpose of holding said pawl up to a position where it cannot act upon the left-hand ratchet-wheel. When this movement of the parts has been effected, the driving-pawl 28 at the right-hand side of the machine is freed from engagement with its ratchet-wheel, and as the writing continues the movement of the ribbon is reversed, or is caused to wind from the left to the right hand side, the frame 41 gradually descending to its normal position as the obstruction 32 recedes.

It will be understood, of course, that when the ribbon has been entirely unwound from the left-hand spool the pin or obstruction 32 at the left-hand end of the ribbon engages similarly with the frame 41 at the left-hand side of the machine, and the projection 44 by the rise of the said frame is caused to act upon the arm 46 and again automatically reverse the direction of the movement of the ribbon.

Referring to Fig. 10, the ribbon-spool frame or support 19 is slotted at 53 on each side arm 130 to receive a pin or bar 54, which rests normally at the bottom of said slots and which is provided with an eye 55 just wide enough to permit the ribbon to pass through. The said bar

- or pin 54 is provided with a lateral extension or projection 56, which is adapted to serve the same purpose that the projecting end of the lever 30 and the projection 44 serve—that is, 5 to actuate the reversing devices through the longitudinal movements of the ribbon. The ribbon, when used with the bar 54, is to be provided with an obstruction or enlargement, as 32, incapable of passing through the eye 10 or slot in the bar 54, so that when said enlargement arrives at the eye or slot and the movement of the ribbon is continued it will operate to lift the bar 54, so as to carry the extension or projection 56 to a position where 15 it may strike against the arm 35 of the lever 34 when this construction is used, or to a position where it may strike against the head 47 when the rock-shaft construction of Figs. 5, 6, and 7 is used. The construction shown at 20 Fig. 10 is to be used at each side of the machine, as before, and is adapted to work, in conjunction with the reversing-levers, to produce the same result as the construction shown at Figs. 8 and 9—namely, to assist in 25 the automatic reversal of the direction of movement of the ribbon lengthwise.

So far as one part of my invention is concerned the back and forth movements of the ribbon may be effected by means other than 30 shown herein, and so far as my improvements relating to the means for moving the ribbon back and forth are concerned the machine may be unprovided with any means for reversing the movements of the ribbon longitudinally.

The switch or means for controlling the action of the driving-pawls, as well as the switch movers or projections actuated by the longitudinal movements of the ribbon, may be 40 greatly varied in detail construction without departing from the gist of my invention.

What I claim as new, and desire to secure by Letters Patent, is—

1. In a type-writing machine, the combination 45 with the ribbon, of the ribbon-spools provided each with a ratchet-wheel, driving-pawls for turning said ratchet-wheels, means for moving the ribbon-spools back and forth, a switch for alternately engaging said driving-pawls, and means, moving with said spools, for automatically actuating said switch operated through the longitudinal movements of the ribbon.

2. In a type-writing machine, the combination 55 with the ribbon, of a pair of reciprocatory ribbon-spools provided each with a ratchet-wheel, driving-pawls for turning said ratchet-wheels, a switch for alternately engaging said driving-pawls, and a device at and 60 movable with each spool adapted to be moved by the ribbon to actuate the said switch.

3. In a type-writing machine, the combination 65 with a ribbon having at or near each end an enlargement, a pair of reciprocatory ribbon-spools provided each with a ratchet-wheel driving-pawls for turning said ratchet-

driving-pawls, and connections between said switch and said ribbon adapted to be acted upon by said ribbon and in turn to actuate 70 said switch during an endwise movement of the spool, whereby the longitudinal travel of the ribbon may be automatically reversed.

4. In a type-writing machine, the combination 75 with a ribbon having at or near each end an enlargement, a pair of reciprocatory ribbon-spools provided each with a ratchet-wheel, driving-pawls for turning said ratchet-wheels, a switch for alternately engaging said driving-pawls, and a switch-mover at each 80 side adapted to travel back and forth with said spools and to be actuated independently by said ribbon and carried to a position to act on said switch.

5. In a type-writing machine, the combination 85 with a ribbon having at or near each end an enlargement, a pair of reciprocatory ribbon-spools provided each with a ratchet-wheel, driving-pawls for turning said ratchet-wheels, a switch for alternately engaging said 90 driving-pawls, and a lever at each side, having an eye or slot, adapted to travel back and forth with said spools and to be vibrated by said ribbon to a position to act on said switch.

6. In a type-writing machine, the combination 95 with a ribbon having at or near each end an enlargement, a pair of reciprocatory ribbon-spools, provided each with a ratchet-wheel, driving-pawls for turning said ratchet-wheels, a vibratory switch for alternately engaging said driving-pawls, and a pair of 100 switch-movers arranged to travel with said spools, and adapted to be actuated alternately by the ribbon so as to act on said switch first on one side and then on the other.

7. In a type-writing machine, the combination 105 with a ribbon having at or near each end an enlargement, a pair of reciprocatory ribbon-spool frames or supports, a pair of ribbon-spools having each a ratchet-wheel, a pair 110 of driving-pawls, a vibratory switch for said pawls and a pair of levers as 30, on said frames for shifting said switch.

8. In a type-writing machine, the combination 115 with the ribbon, of a pair of reciprocatory ribbon-spools, a set of devices for rotating each of said spools, a switch to coöperate with said rotating devices, and a pair of switch-movers actuated by the movements of the ribbon.

9. In a type-writing machine, the combination 120 with the ribbon, of ribbon-spools provided each with a ratchet-wheel, driving-pawls for turning said ratchet-wheels, means for moving the ribbon-spools back and forth, a switch for alternately holding said driving-pawls in proper relationship to turn their respective ratchet-wheels, and means moving with said spools and operated through the longitudinal movements of the ribbon for automatically 125 throwing one driving-pawl into engagement and the other out of engagement with its respective ratchet-wheel.

10. In a type-writing machine, the combina-

- tion with the ribbon, of reciprocatory ribbon-spools provided each with a ratchet-wheel, a pair of driving-pawlS for alternately turning said ratchet-wheels, and means, for reversing said pawls, moving with said spools and controlled by the movements of said ribbon.
11. In a type-writing machine, the combination with the ribbon, of a pair of reciprocatory ribbon-spools provided each with a ratchet-wheel, a pair of switch-connected driving-pawlS, and means for reversing said pawls carried by the ribbon-spool frames or supports, and alternately and automatically moved into operative positions for reversing said pawls at or about the end of the longitudinal travel of the ribbon, and operating to effect the reversal of the pawls during end-wise movements of said reciprocatory ribbon-spools.
12. In a type-writing machine, the combination with the inking-ribbon, of a pair of reciprocatory ribbon-spools, a set of devices for rotating each of said spools, a switch mechanism to coöperate with said rotating devices, and means carried by the ribbon-spools and under the control of the ribbon for alternately reversing the ribbon-spool-rotating devices.
13. In a type-writing machine, the combination with the ribbon, of a pair of reciprocatory ribbon-spools having each a ratchet-wheel, a driving-pawl mechanism consisting of a pair of pawls and a controlling-switch, and means on the ribbon-spool frames or supports, controlled by the movements of the ribbon, for actuating the driving-pawl mechanism and automatically throwing one pawl out of engagement and the other pawl into engagement.
14. In a type-writing machine, the combination with the paper-carriage, and its driving-power, of a ribbon, a pair of ribbon-spools, a transverse rock-shaft, a strap or chain 13, connected to the power-shaft, a rocker-arm 14, a pair of rocker-arms 18, connected to the ribbon-spools, a returning-spring, a set of devices for rotating each of said spools, a switch to coöperate with said rotating devices, and a pair of switch-movers actuated by the longitudinal movements of the ribbon.

Signed at New York city, in the county of New York and State of New York, this 12th day of June, A. D. 1891.

W. J. BARRON.
